UNITED STATES PATENT OFFICE.

HARRY L. PECK, OF CHICAGO, ILLINOIS.

COIN-CONTROLLED BOOK-HOLDER.

SPECIFICATION forming part of Letters Patent No. 644,776, dated March 6, 1900.

Application filed June 23, 1899. Serial No. 721,523. (No model.)

To all whom it may concern:

Be it known that I, HARRY L. PECK, of Chicago, in the county of Cook and State of Illinois, have invented certain new and useful 5 Improvements in Coin-Controlled Book-Holders; and I do hereby declare that the following is a full, clear, and exact description thereof, reference being had to the accompanying drawings, and to the letters of reference marked thereon, which form a part of this 10 specification.

This invention relates to improvements in coin-controlled devices, and more particularly to that class designed to hold a book normally in a closed position, but which will permit the book to be opened when the coin-controlled mechanism is operated by the insertion of a coin of a designated dimension in the slot thereof.

20 The object of my invention is to provide a device that shall hold an ordinary city directory. It will be fully understood by reference to the accompanying drawings and the description thereof and will be more specifically stated in the claims appended hereto.

Referring now to the drawings, Figure 1 illustrates in a perspective view a suitable table provided with my invention. Fig. 2 illustrates a modification thereof, consisting of a 30 box provided with my invention. Fig. 3 is an enlarged plan view of the device with the book removed. Fig. 4 is a longitudinal vertical sectional view taken centrally upon Fig. 3. Figs. 5 and 6 are vertical transverse sectional views looking in opposite directions.

In said drawings, A represents as a whole any suitable table having a suitable opening therethrough, as shown at a. B represents a box comprising side walls b, front end wall b', rear end wall b'', and bottom wall b''. The box B is conveniently secured to the under side of the table A and is of such a size as to register with said opening a, as will be fully understood by reference to the various figures 45 of the drawings. Where it is desired to have the coin-controlled device a portable affair—that is, disconnected from the table—the box B may be substantially as shown in Fig. 2. When in this form, it may be conveniently 50 used upon a shelf or counter in the drug-store or other convenient place. The interior mech-

anism will in such case be the same as that used in the other table form of the device.

On either side of the opening in the table and extending longitudinally therein is a 55 hinged metal frame C, carrying at its upper portion a wooden plate c and having on its lower portion c' and extending at right angles to such lower portion a toothed segment C'. As shown in Fig. 5, these toothed segments mesh with each other when the frames C are rotated about their respective pivots or hinges c². Near each end of the plates c and spanning the space between them are the flexible loops of rawhide or the like C². A 60 city directory or other book D will be placed in position by resting its back upon the loops C², as indicated in Figs. 1 and 2, in which position the sides of the book d will be parallel and in contact with the plates c. Preferably 65 the sides d of the book will be removably secured to said plates c by screws d' or in any convenient manner.

Projecting inwardly from the sides b of the box B are hinged locking-arms E, pivoted to 70 the said sides at e and each being provided with a shoulder e' adapted to engage and lock the extreme lower end portion c' of the frame C. A spring e², secured at one end of the side b of the box and pressing with its 75 free end upon the under side of the locking-arm E, tends to hold said arm in its horizontal or locking position, as illustrated in Fig. 5. In this position frames C are upright and the directory or other book D is held firmly 80 in position between said plates c, in which position the book may not be opened for the inspection of its contents until the locking-arms E have been withdrawn.

Of course it will be understood that in using 85 my invention, for example, in connection with a city directory the boxes will be built of a size required to hold the book snugly in its locked or closed position, as shown in Figs. 1 and 5, and by such frictional contact 90 the book may not be withdrawn from between the plates c even should the screws or other fastening device d' be dispensed with.

I will now describe the mechanism for releasing the locking-arms E. This consists of 95 a transversely-arranged rocking bar or rod F, having at each end a right-angled exten-

sion-arm f , the outer ends of which arms rest upon the inner or free ends of the locking-arms E . Secured in a vertical position above the center of the rocking-bar F is a relatively-
5 wide flat arm f^2 . f^3 are suitable bearings for the rocking bar F . From this construction it will be manifest that the pushing of the free end of the arm f^2 inwardly—that is, toward the center of the box—will rock the bar
10 F , and consequently depress the outer end of the arms f and locking-bars E , thus releasing the shoulders e' of said bars E from engagement with the lower ends c' of the frames C . This movement is accomplished
15 by means of the push rod or bar G , the outer end of which projects beyond the outside of the box and the inner end of which is located adjacent to said arm f^2 when a coin is in position. H is the coin-slot, h the coin-chute, and h' the holder for the coin after it has left the chute. When the coin is in the holder h' , the push-button G is pressed inwardly, strikes the coin, and presses it and the arm f^2 inwardly, as indicated in dotted lines in Fig.
20 4. The lower portion of the holder h' is provided with a shoulder h^2 , on which the coin rests until it is pushed inwardly by the push-rod G . As soon as the rod G has been moved to the limit of its inward movement a spring
25 g , wrapped about the inner end of said rod, exerts a pressure sufficient to retract the rod G and move it to its outer or normal position. It may be, however, that the person using the device has moved the push-rod and
30 released the locking-arm E , but has not actually opened the book. In such event to prevent the rocking arm f^2 from moving back, as it would do under the influence of the spring e^2 and the upward movement of the locking-arm
35 E , I provide locking-dogs I . These dogs are pivoted at i and are operated in one direction by gravity. They have a limited movement in either direction, as indicated, by the pins i' and are each provided with a projecting
40 nose i^2 . The nose i^2 falls down upon the free ends f of the rock-bar F as soon as the locking-arm E is pressed down. They thus hold the vertical plate or arm f^2 in the inclined position indicated by the dotted lines in Fig. 4,
45 and it will be manifest, therefore, that when said arm is in its inclined position the coin will drop through the chute h adjacent thereto and into the coin-receptacle immediately upon the push-rod G being released and re-
50 tracted. The operator may then open the book by taking hold of the upper or free ends of the plate c , the frames C turning on their hinges c^2 , the movement being facilitated by the intermeshing of the toothed segments C' .
55 As the free ends c' of the frame move toward each other upwardly, as indicated in dotted lines in Fig. 6, they will engage an upwardly-projecting shoulder i^3 upon the gravity-dogs I and move the upper ends of said dogs toward each other. This movement disengages the outwardly-projecting nose i^2 of each

dog from the ends f of the rock-bar F . The lock-arm E thereupon at once assumes its normal position under the influence of the springs e^2 .
70

In order that the open book may not be consulted for too long a time or may not remain open, I have arranged for an automatic closing of the same. My arrangement for accomplishing this result comprises a plurality of 75 springs. Some of these springs are ordinary coil-springs J , the lower ends of which are suitably secured at j to the interior of the bottom b^3 of the box, while the upper ends of said springs are secured to projecting arms 80 c' upon the frame C . Another of said springs is shown at K , the same consisting of a flat spring secured at its lower end at k to the side b of the box and projecting at its upper or free end against a suitable projection or 85 knob k^3 upon the frame C . It will now be manifest that when the book is opened the frames C and the plates c will lie in a substantially-horizontal position, as indicated in Fig. 6, and that they will remain in such position so long as a very slight or minimum pressure, such as the weight of the hand, is laid upon the open book. It will also be understood that as soon as this pressure of the hand is removed the frames C , acting under 90 the influences of the springs J and K , at once resume their vertical and normal positions, thus closing and locking the book.
95

To provide against the unlocking of the device without the insertion of a coin, I provide 100 a slot or opening f^4 through the arm f^2 of sufficient size to freely admit the inner end of the push-rod G , from which it will be noted that when the push-rod G is operated it in turn will not operate the rock-bar F unless 105 the coin has been inserted in the chute, rests upon the shoulder h^2 , and forms a closure for the opening f^4 . I desire it to be understood, however, that the particular coin-operating device here illustrated does not comprise the 110 sum and substance of my invention, inasmuch as any device for receiving and conducting the coin and operating a push-button for the purpose of tilting the rock-bar F can be substituted for the specific device here illustrated 115 and can be combined with the other features of my invention without departing from the spirit thereof; nor do I desire to be limited to the specific form of the other features of my invention herein shown and described, but 120 do desire that my claims shall be construed to cover all mechanical equivalents thereof.

I claim as my invention—

1. In a coin-controlled book-holder, the combination with a pair of pivoted frames, of pivoted locking-arms independent of the frames and adapted to engage the same only in their closed position, a single device for simultaneously releasing said pivoted locking-arms, and coin-controlled means for operating said 125 single device.

2. A book-holder, comprising a table pro-

vided with an opening, a pair of frames pivotally secured one on either side of said opening, flexible connections between said frames upon which the back of a book may rest, toothed segments on said frames adapted to intermesh with each other, a pivoted locking-arm adapted to engage a movable part of one frame, a coin-controlled device for releasing said arm.

30 5. In a book-holder, the combination of a pair of upright movable frames, between which the book may be secured in its closed position, locking devices for holding said frames in said upright position, controlled mechanism for withdrawing said locking devices, and a pivoted gravity pawl or dog adapted to engage said controlled mechanism and retain the locking device in a retracted position during a portion of the movement of the frame when opening the book.

35 6. In a coin-controlled book-holder of the character described, the combination of the frame c' , the spring-actuated lock-arm E, the gravity-dog I having a projecting nose i^2 and projection i^3 , and coin-controlled means for actuating said locking-arms E.

40 In testimony that I claim the foregoing as my invention I affix my signature, in presence of two witnesses, this 20th day of June, A. D. 50 1899.

HARRY L. PECK.
